UNIT HEATER AND AIR CONDITIONER

Clayton A. Dunham, Glencoe, and David N. Crosthwait, Jr., Chicago, Ill., assignors to C. A. Dunham Company, Marshalltown, Iowa, a corporation of Iowa

Application February 4, 1938, Serial No. 188,598

1 Claim. (Cl. 257—137)

This invention relates to certain new and useful improvements in an air-conditioner unit adapted to be positioned similarly to an ordinary radiator within a room, and designed to either 5 heat or cool the air within a room, humidify the air, and ventilate the space by introducing a desired proportion of fresh air.

This unit is designed to form part of a suitable heating or cooling system which supplies 10 the unit with the heat-transfer fluid medium, for example steam in winter and cold water in summer. It is well known that, on the average, about three times as much heat transfer surface is required to adequately cool the air when the 15 cooling medium used is within the range of 40° to 50° Fahrenheit, as is required to heat the same space with steam in the temperate zone. A suitable radiator or heat-transfer device is provided which automatically provides for this 20 change in heat-transfer surface as the temperature requirements vary.

Briefly described, the novel unit comprises a suitable hollow metallic casing having a louvered outlet opening in the top, and a similar inlet 25 opening in the lower portion of the front wall. A second inlet opening in the lower portion of the rear wall connects with a conduit for introducing fresh outside air. The casing comprises a removable top member, and a front and end 30 wall unit that may be detached from the back wall and removed after the top has been lifted off. The main supporting portion of the frame structure comprises the rear wall and a pair of vertical forwardly extending partitions that are 35 spaced somewhat from the respective ends of the rear wall. Within the air-treating space between these partitions is housed at the top the heating or cooling radiator and the humidifier, and at the bottom, above the inlet openings, extends a suitable filter through which the inflowing air must pass. Between the filter and the heating and cooling unit is positioned a suitable 40 blowing mechanism which creates the circulation of air upwardly through the housing. An adjustable damper mounted beneath the filter and 45 between the two inlet openings determines the relative proportions of the fresh and re-circulated air which are drawn upwardly through the filter and treated by the tempering and humidifying mechanism. The supply and return piping, valves, and regulating and adjusting mechanisms are positioned in the end spaces beyond the partitions and between these partitions and the removable end walls.

50 The principal object of this invention is to pro-

vide an improved air-conditioner unit of the type briefly described hereinabove and disclosed more in detail in the specifications which follow.

Another object is to provide an improved radiator or heat-exchange unit, the effective capacity of which is suitably and automatically varied in accordance with the use of heating or cooling medium therein.

Another object is to provide an improved humidifier adapted to be used in connection with the heat exchanger so that the temperature of the water is automatically controlled.

Another object is to provide an improved blower assembly for properly directing the air stream or streams toward all portions of the heat exchanger.

Another object is to provide an improved means for supporting and cushioning the blower assembly.

Another object is to provide auxiliary draft 20 openings for automatically permitting a free air circulation upward through the casing when the blower is not in operation.

Another object is to provide an improved form of adjustable damper mechanism for proportioning the amounts of fresh and re-circulated air introduced into the conditioning unit.

Another object is to provide an improved form of casing having readily detachable parts for enclosing the tempering and air-circulating mechanism and providing ready access thereto.

Another object is to provide an improved louver construction for use in a casing of the above type.

Another object is to provide an improved inlet 35 valve for adjustably regulating the flow of either cooling or heating medium to the heat-exchanger.

Other objects and advantages of this invention will be more apparent from the following 40 detailed description of certain approved forms of mechanisms constructed and operating according to the principles of this invention.

In the accompanying drawings:

Fig. 1 is a front perspective view of the assembled unit with the enclosing housing in position.

Fig. 2 is a similar perspective view but looking at the housing from the rear.

Fig. 3 is a larger perspective view of the front 50 of the assembly with the front, end and top walls removed.

Fig. 4 is a plan view of the assembly, with a central portion broken away, and the top or cover removed.

Fig. 5 is a detail view of one of the latching assemblies for holding the end walls to the rear wall.

Fig. 6 is a perspective view of one of the latch members.

Fig. 7 is a detail view of one of the louver assemblies.

Fig. 8 is a detail view showing how one of the slats or louvers is secured in position.

Fig. 9 is a transverse vertical section, on a larger scale, taken substantially on the line 9—9 of Fig. 3.

Fig. 10 is an enlarged detail section, taken on substantially the same plane as Fig. 9 through the humidifier, but showing the cover in partially elevated position.

Fig. 11 is a transverse vertical section taken substantially on the line 11—11 of Fig. 3.

Fig. 12 is a detail longitudinal vertical section taken substantially on the line 12—12 of Fig. 11.

Fig. 13 is an enlarged vertical section through the radiator or heat exchanger, with the greater portion of the center of the assembly broken away.

Fig. 14 is a horizontal section through one end portion of this heat exchanger, the view being taken substantially on the line 14—14 of Fig. 13.

Fig. 15 is a detail longitudinal vertical section through one of the blowers, the view being taken substantially on the line 15—15 of Fig. 9.

Fig. 16 is a detail elevation of the worm gearing for adjusting the damper.

Fig. 17 is a longitudinal vertical section through the blower-supporting panel showing the auxiliary draft doors in the panel.

Fig. 18 is a vertical central section through the inlet valve, the view being taken substantially on line 18—18 of Fig. 19.

Fig. 19 is a plan view of the valve.

Fig. 20 is a detail vertical section taken substantially on the line 20—20 of Fig. 2.

The assembly comprises in general the enclosing casing or housing A, the heat-exchanger unit B, the humidifier C, the blower assembly D for enforcing the air circulation through the housing, the filter E, the adjustable damper mechanism F, and the improved inlet valve G.

The frame A which is formed of sheet metal parts comprises an upright rear wall 1 having 50 inturned flanges 2 and 3 at its respective ends and also similar inturned flanges along parts of the top and bottom. Forwardly extending vertical partitions 4 and 5, also formed with flanges along their several edges, are secured to the rear 55 wall 1 along lines spaced inwardly from the ends of the rear wall so as to provide a space between the partitions in which the greater portion of the air circulating and tempering mechanism is mounted. These features are for the greater 60 part supported on these partitions, as hereinafter described. The partitions 4 and 5 extend above the rear-wall 1, as clearly shown in Figs. 3 and 20, and support the removable top or cover member as hereinafter described. The end spaces beyond the partitions 4 and 5, and between these 65 partitions and the outer end walls, are adapted to house the piping, valves, adjusting mechanism, etc., as hereinafter referred to. The supply piping will ordinarily go out through the open bottom of the casing, but openings 6 and 7 are provided in the lower portion of rear wall 1 communicating with the end spaces so that these pipes may be extended laterally outward through an adjacent wall of the building. An inlet air 70 opening 8 is also formed in the lower portion of 75

rear wall 1 and communicating with the space between the partitions 4 and 5. Inturned flanges 9 integral with rear wall 1 are formed around the sides and ends of the opening 8 and a rectangular frame 10 is secured to these flanges 5 within the opening (see Fig. 9). The end of any suitable conduit 11 can be connected with this frame 10, the conduit 11 extending through an adjacent wall and communicating with the outer air so that fresh air can be drawn in through 10 the inlet 8. If the fresh air inlet is not to be used, a suitable closure can be fitted in or on flanges 9 so as to block up the opening 8.

The front wall 12 is rounded at the ends 13 and has end walls 14 formed integrally therewith, the end walls 14 being bent parallel to the rear wall 1 at 15 and terminating in inwardly extending flanges 16 (see Fig. 4) which are adapted to fit against and parallel to the end flanges 2 on the rear wall. 20

Pivoted on one of each pair of flanges 2 and 16 are a pair of similar latch members 17 (see Figs. 4, 5 and 6). These latches are disposed near the top and bottom of the casing respectively. Each latch is pivoted at its lower end 25 18 so as to swing inwardly, and when swung up to operative position the yoke 19 at the upper end of the latch member is adapted to engage over the mating flanges 2 and 16 and lock same together. An upright operating rod 20 is pivoted at 21 and 22 to the two latches and is provided at its upper end with a handle 23 which is accessible to operate the latches when the cover 24 of the casing is removed. 30

A bottom frame member 25 is suitably secured 35 to the partitions 4 and 5 and is provided with an upstanding flange 26 along the front of the assembly between the partitions.

A second inlet opening 27 for re-circulated air is provided in the lower portion of front wall 12 40 so as to be substantially opposed to the inlet opening 8 in the rear wall. Inturned horizontal flanges 28 and vertical flanges 29 are formed around the sides and ends of the opening 27. The lower flange 28 rests on the upright flange 45 26 of the bottom member, and an angular strip 28' (see Fig. 9) is secured to the under side of flange 28 so as to lock the front wall to the bottom flange 26 when the front and end wall assembly is pushed inwardly and downwardly 50 into position.

The inturned end flanges 29 are provided with a plurality of parallel slots 30, preferably arranged at an angle to the horizontal, and in these slots are secured the ends of the slats or louvers 55 31. Preferably these louvers are notched at their ends as indicated at 32 (Fig. 8) so that the outer edges of the louvers will be substantially flush with the outer face of the casing, and the end portions of the louvers project through the slots 60 33. and are welded to the flanges 29 as indicated at 33.

Preferably ornamental strips or ribs 34 are secured horizontally around the lower portion of 65 the front and ends, and a similar strip 35 is secured around the lower edge of the cover 24. An inner metal strip 36 is welded to the outer face of the wall member 12 or 14, and the bowed outer ornamental strip 34 or 35 (preferably formed of some bright or highly polished ornamental metal) is snapped into place or pushed endwise onto this inner holding strip 36 (see Figs. 9 and 10). In this manner the ornamental strips 70 are firmly but removably mounted so that any 75

ordinary accidental impacts will not result in jarring the strips loose.

The removable cover member 24 fits over the upwardly extending end portions of partitions 4 and 5 and rests on the felt strips 24' carried by these partitions, and is provided with short downwardly extending front and rear walls 37 and 38 and end walls 39 adapted to match with and form extensions of the similar walls of the main housing. The lower edge of the front wall 37 of the cover is provided with an inturned flange 40 and the ornamental rib 35 is so secured to the front and end walls of the cover as to project downwardly over the main front and end walls. An angular strip 41 having an upturned inner flange 42 is secured to the under face of flange 17, and the flange 40 is adapted to bear against flange 42 so as to press this flange against cushioning strip 42a carried by the frame member 42b mounted at its ends to vertical partitions 4 and 5.

The main end walls 14 and the end walls 39 of the cover are provided with inturned flanges 14' and 39', respectively, and a latch member 17' of the type shown in Fig. 6 is pivoted on each flange 14' and may be swung to the position shown in Fig. 20 to lock the cover in place.

An upper outlet opening 43 is formed in the top of cover 24. This opening may be louvered and formed in all respects the same as the opening 27 in the front wall as already described. Access openings are formed in the end portions of cover 24 above the end spaces beyond the partitions 4 and 5, these openings being normally closed by pivoted doors 44. Each of these doors is pivoted on an axis 45 spaced somewhat from one edge thereof and a torsion spring 46 secured about this axis serves to normally hold the door closed against a stop 47. By simply pushing in on the short extension 48 at one side of pivot 45 the door may be swung to open position thus giving access to the latches 17' and to certain other mechanisms in the end spaces. After the latches 17' are released the cover 24 can be bodily removed so as to expose the mechanism as shown in Fig. 4. To provide additional access to the parts the latches 17 can be unlocked and the front and end walls removed so as to expose the entire assembly as shown in Fig. 3.

The improved heat-exchanger B is built up from a plurality of thin metal tubes 49 mounted at their ends in suitable headers and provided with a plurality of thin metallic fins 50 and 51 to increase the radiating or heat-exchange surface. While the number and arrangement of these tubes 49 could be varied, in the example here shown these tubes are arranged in three substantially horizontal tiers of five tubes each, the tubes of each successive tier being staggered so as to be positioned beneath the spaces between tubes of the adjacent tiers thus providing a maximum surface contact with the upwardly flowing air. The heating or cooling medium is introduced into one end of the tubes of the upper tier, and thence flows alternately back and forth, through the successive tiers. For this reason the successive tiers are inclined slightly from the horizontal to facilitate drainage.

The fluid heating or cooling medium is introduced through inlet pipe 52 provided with inlet control valve 53 (a preferred form of which is hereinafter described more in detail) into the header 54 (Figs. 13 and 14) into which is connected one end of each of the upper tiers of tubes 49. An internal web 55 (which may be provided

with openings 55') serves to equalize the distribution between the several tubes 49. It will be noted that in the example here shown the tubes 49 are of oval cross-section with the greatest diameter positioned vertically.

At opposite ends of the heat-exchanger the upper and next lower tiers of tubes 49 are connected by the header 56 divided by an internal web 57 having a port 58 adapted to be closed by a movable valve member 59 carried by the thermostatic disk 60. This functions the same as the usual thermostatic-trap so that when steam is used as a heating medium and the chamber 61 becomes filled with steam disk 60 will expand and cause valve member 59 to close the port 58. In this manner, when steam is used as a heating medium the steam is confined to the uppermost tier of tubes 49. When condensate accumulates in chamber 61 the trap will open and permit this condensate to drain out through port 58.

The intermediate and lower tiers of tubes are connected at the opposite end by the header 62 (it will be noted that there is no connection between headers 54 and 62), while at the other end the lower tier of tubes drains into a header 63 from which directly extends the return or drain pipe 64.

It will be noted that when steam is used as a heating medium only the upper tier of tubes is filled with steam, but the condensate must drain through the two lower tiers on its way to the drain pipe 64, and thus these lower tiers will act as an economizer to extract the maximum quantity of heat from the hot water.

Although separate fins on each pipe, or each tier of pipes, could obviously be used, it will be noted that as here shown continuous fins 50 are mounted on both the upper and intermediate tiers of pipes. In this manner the fins of the intermediate tier serve as additional radiating surface for the upper steam-filled pipes. These fins 50 are intermediately crimped or bowed as indicated at 65 in Fig. 13 thereby permitting the two series of pipes 49 to be inclined somewhat with relation to one another for drainage purposes. The intermediate bowed portions 65 of the fins also serve to impede the progress of the upwardly flowing air and thus provide for greater heat-transfer. The second series of fins 51 are mounted only on the lower tier of pipes 49. Obviously this arrangement of the radiating fins could be varied as desired.

When the heat-exchanger is used for cooling purposes and cold water is passed through the pipes or conduits, the trap 60 will remain open and the cold water will flow continuously through all three tiers of pipes so that all portions of the heat-exchanger will be equally effective. This is essential since greater heat-exchange surface is necessary during the cooling season since the temperature of the cooling medium does not differ as greatly from the prevailing air temperature as does steam during the heating season.

It will be noted that the heating or cooling medium and the air flow in opposite directions, that is the upwardly flowing air stream encounters the lower cooler pipes (during the heating season) and encounters the upper hotter pipes after the air has been somewhat preheated. This is the most effective system for heat-exchange. The same is true, with a reversal of temperatures, during the cooling season.

In summer, when the apparatus is used for cooling purposes, moisture will precipitate out

of the air incidental to the cooling process and for the purpose of collecting this moisture a plurality of V-shaped troughs 67 (Figs. 9 and 11) are arranged beneath the heat-exchanger B so as to collect this moisture. These troughs are arranged in two tiers, staggered with relation to each other, so as to not interfere with the upward flow of air through the casing but at the same time provide a continuous collecting surface. These troughs are supported at their respective ends on the partitions 4 and 5 and are inclined somewhat toward one end (Fig. 11) where the troughs discharge into a receptacle 68 from which extends a drain pipe 69.

15 The humidifier C comprises a tank 70 (Fig. 10) which is secured closely adjacent the heat-exchanger B so that the body of water 71 in the humidifying tank will be heated from the heat exchanger. The body of water 71 is maintained at substantially constant level by the introduction of water from a supply pipe 72 (Fig. 3) through valve 73 automatically controlled by float 74, in well known manner. A heating coil consisting of a plurality of pipes 75 is positioned in tank 70, the inlet end of this coil being supplied with steam from the main inlet pipe 52 through a branch pipe 76 provided with a control valve 77. The coil 75 discharges at its other end through pipe 78 and steam-trap 78' into the main drain pipe 64. An intermediate partition or baffle 79 positioned in tank 70 causes a convection circulation of the water so as to equalize the temperature at the surface of pool 71. The tank 70 is preferably metallic so as to readily transmit heat from the heat exchanger B, and is open at its top.

An upwardly extending air passage 80 is formed between the front wall of tank 70 and a baffle member 81 suitably mounted on the upper frame member 42^b. A closure member 82 pivoted at 83 is adapted to close the top of passage 80 and tank 70 as shown in Fig. 9, in which case no air flows through the passage 80 and the humidifier is ineffective. An adjusting screw 84 has a universal central connection 85 with cover 82 and a universal connection 86 with tank 70, and by means of this adjusting screw 84 the cover 82 can be raised to any desired position so as to permit a restricted flow of air through passage 80, then in contact with the surface of the heated pool of water 71, and thence through the upper portion of the heat exchanger and out through outlet 43, all as indicated by the arrows in Fig. 10. By thus permitting a portion of the air stream to flow in contact with the water supply in the humidifier, a desired proportion of watery vapor can be added to the main air stream.

It will be noted that when this humidifying device is used in connection with a differential heating system, that is one that is varied in accordance with outside temperature changes, it will be automatically set so as to maintain substantially uniform inside humidity. With a constant quantity of fresh air admitted and with the temperature of the heating coil varying directly with the weather conditions, the rate of heat transfer from the heating coil to the water is in substantially direct proportion to the temperature of the outside air so that with the humidifier construction as shown the rate of vaporization of water will be inversely proportional to the temperature of the outside air which is the same as being inversely proportional to the weight of moisture in the air initially so that in

extreme weather greater quantities of moisture will be added and in milder weather lesser quantities, thus insuring the maintenance of the desired humidity. Since the cubical air contents of the room to be supplied with air by this air-conditioner will vary in practice, the position of cover 82 can be adjusted by means of screw 84 so as to obtain the desired humidity adjustment in accordance with the capacity of the room. When once adjusted this adjustment will not ordinarily have to be changed for any particular installation of the unit.

The filter E (see Figs. 3, 9 and 12) is of rectangular form and comprises the filtering material 87 enclosed between a pair of wire screens 88 and held in an outer metallic frame 89. The frame 89 is adapted to be slipped laterally into position in a pair of metallic brackets 90 mounted on the partitions 4 and 5. When in position the side edge portions of the filter will rest on the inturned flanges 28 and 9 respectively of the front and back walls so that all of the air drawn into the casing through inlets 27 and 8 must pass upwardly through filter E.

The damper F determines the proportions of fresh and re-circulated air that are drawn into the housing. This damper F (see Figs. 3, 9, 11 and 12) is pivotally mounted at its lower edge on a shaft 91 mounted in partitions 4 and 5 near the bottom of the casing. The damper is of rectangular form but is telescopic so as to be of variable width, being composed of a hollow lower member 92 into which telescopes the flat upper member 93. Each of these members may be provided with strengthening ribs as indicated at 94. The damper is made telescopic so that the upper edge of member 93 may be maintained closely adjacent the lower surface of filter E in all positions of the damper. The upper damper member 93 is supported near its upper outer corners by brackets 95 carrying rollers 96 movable in trackways 97 mounted on the partitions 4 and 5 substantially parallel to the position of filter E. Preferably each roller 96 is of the type provided with an interior series of ball bearings 98 as indicated in Fig. 11 so that free rolling movement of the support is possible with the application of very little effort to the supporting shaft 91.

Any suitable means may be provided for adjusting the position of the damper. As here shown shaft 91 is provided at one end with a worm wheel 99 meshing with a worm 100 on the lower end of a vertically extending adjusting shaft 101. Shaft 101 is provided at its upper end with a handle 102 by means of which the shaft may be manually rotated so as to suitably position the damper F. It will be understood that the damper might be motor-operated if so desired.

It will be seen that with the damper in the extreme forward position indicated in Fig. 9 only fresh air will be admitted to the unit through the rear inlet 8. If the damper is adjusted to its other extreme position only re-circulated air will be admitted through the front inlet 27. If the damper is in some intermediate position such as shown in Fig. 11, the air stream flowing through the unit will consist of desired proportions of fresh and re-circulated air.

It will also be noted that should a strong wind or draft tend to blow through the lower portion of the casing, this air will be deflected upwardly by damper F and consequently cannot chill the feet of occupants of the room.

A stop screw 103 may be provided (Fig. 11) to prevent the roller 96 from leaving its guide, and felt strips 104 mounted on the end partitions 4 and 5 may be provided to prevent fresh air from leaking past the damper when in extreme rear position.

The blower assembly indicated generally at D is positioned in the chamber between filter E and the upper heat exchange and humidifying units. This assembly comprises a pair of spaced apart similar centrifugal fans or blowers 105 and 105', and an intermediate driving motor 106. This assembly is supported by the rectangular panel 107 carried at its ends on the vibration-dampers or cushions 108 (Fig. 11). These cushions comprise inner parts 109 bolted at 110 to the panel 107, and outer members 111 mounted on the brackets 112 (Fig. 3) secured on the partitions 4 and 5. The rubber cushions 113 are vulcanized between the members 109 and 111 so that the load will be taken up by a shearing stress on the rubber. In this manner the resilience is kept at a maximum and vibrations are minimized. It will be understood that motor 106 is suspended in suitable cushioned supports from the bottom of the central portion of panel 107.

Each blower 105 or 105' (see Figs. 9 and 15) comprises an inner cage structure 114 comprising a series of curved vanes 115 carried by disk 116 and mounted on one end of motor shaft 117. This cage rotates within a drum-shaped housing 118 which has a peripheral spiral form, that increases somewhat in diameter in the direction of rotation of the cage 114. The ends 119 of the housing are provided with central inlets 120, preferably curved inwardly at their edges, and the air stream is expelled through an outlet 121 in the top of housing 118 and extending through panel 107. A pair of similar deflectors or baffles 122 are positioned within housing 118 so as to partially surround the rotating cage as shown in Figs. 9 and 15. These baffles are spaced inwardly from the end walls 119 of the housing and diverge from one another in an upward direction so that the air projected upwardly through outlet 121 by the centrifugal blower will be spread fanwise as it flows upwardly toward the heat exchanger. In this way the air streams projected upwardly by the two blowers will be distributed over those portions of the heat-exchanger above the motor and the space intermediate the two blowers, as well as the spaces beyond the ends of the blowers. The motor 106 is preferably of the three-speed or multi-speed type and is conveniently controlled by switch 123 (Fig. 4) accessible through one of the doors 44 in the top closure.

It will be noted that strips of sponge rubber or felt 124 (Figs. 9 and 11) are positioned around the supporting panel 107 to minimize vibration and seal this outer space, and similar dampening strips are used at various other locations in the unit.

It is desirable at certain times, particularly during the heating season, to operate this device without the use of the blowing mechanism, that is rely upon natural draft to cause the upward flow of air through the casing and in contact with the heat-exchanger B. Under certain conditions this method of operation will be satisfactory, slightly more economical, and will be somewhat more noiseless due to the fact that the fans or blowers are not in operation. The free flow of air upwardly through the casing may be

somewhat facilitated by removing the filter E which may be withdrawn laterally from its supporting frames 90.

To facilitate a free flow of air through panel 107 when the blowers are not in operation, auxiliary passages 125 are provided through the floor of the panel between the blowers and beyond the ends thereof. These passages 125 (Fig. 17) are provided with closures 126 pivoted somewhat off-center at 127 so that the arm of the closure which swings upwardly will be of greater area than the arm which swings downwardly. Small torsion springs 128 may be provided to normally swing these closures to the upwardly sloping open positions shown in Fig. 17, and this is the position that the closures will assume when the blowers are not in operation. When the blowers are operating a higher pressure will be created above the panel 107, and this pressure exerted on the larger upwardly extending portions of the closures 126 will swing them to a substantially horizontal closed position so as to cut off the flow of air through passages 125. As soon as the blowers cease to operate these closures 126 will automatically swing open and permit the free flow of air through passages 125 in addition to the circulation through the blower passages 121.

A preferred form of inlet valve G is shown in Figs. 18 and 19. This valve comprises a casing 129 having an internal web 130 provided with an upper valve seat 131 and an internal passage 132. When the valve is open the heating or cooling medium will flow in through the lower inlet 133 and out through side outlet 134 to the heat exchanger. A movable valve member 135 is adapted to engage valve seat 131 to close the valve. The valve member 135 is raised or lowered by stem 136 connected with nut 137 engaging in an internal nut 138 rotated by handle 139. A continuous sealing diaphragm 140 connected at its lower end to the movable valve member 135 and at its upper end to the valve casing tends to prevent the escape of steam or other medium through the upper end of the valve casing. The valve as thus far described is well known in the art.

To the bottom of movable valve member 135 is affixed a cylindrical sleeve 141 adapted to fit slidably within the valve port or passage 132. The upper cylindrical portion of this sleeve is formed with a plurality of downwardly diverging tapered slots 142 so that as valve member 135 is raised from its seat these slots will be successively uncovered to a greater extent thus providing a gradually increased flow of fluid through the valve. When the sleeve is raised to the extreme position shown in Fig. 18, only the small guide strips 143 remain in passage 132 and the flow of steam through the passage is substantially unobstructed.

The upper rotatable operating portion of the valve is provided with a pointer 144 movable over the dial 145 fixed to the upper portion of the valve casing. When the valve is in completely closed position the pointer will be at substantially the location indicated at 146. As handle 139 is swung in a counterclockwise direction (Fig. 19) the pointer will pass successively over the portion of the dial calibrated in gallons per minute. This indicates the flow of cooling liquid through the valve. For example when the pointer is at the numeral 2, the slots 142 in sleeve 141 will be uncovered to such an extent that a flow of two gallons per minute of cooling liquid will pass through the valve. When the handle is swung

to such an extent that the pointer 143 is on the portion of the dial marked "open" the sleeve will be raised to the extreme position shown in Fig. 18 so that a free flow of steam is permitted. This 5 will be the position of the valve used for heating purposes.

We claim:

In an air-conditioner unit, a casing having an air inlet opening in the lower portion thereof and 10 an air outlet in the upper portion, a heat-ex-
change unit in the upper portion of the casing, and means for enforcing an upward flow of air through the casing comprising a panel supported substantially horizontally through the central 15 portion of the casing and blower mechanism sus-
pended adjacent the panel and adapted to draw

air from the space beneath the panel and force this air through openings in the panel into the space above the panel and thence in contact with the heat-exchanger, and means for permitting a free convection circulation of air upwardly 5 through the casing when the blower mechanism is not in operation comprising auxiliary openings in the panel, pivotally mounted closures for these auxiliary openings, springs for automatically moving the closures to open position, the closures 10 being moved to and held in closed position by the increased pressure in the space above the panel when the blower is operating.
